UNITED STATES PATENT OFFICE

132,316

DESIGN FOR A COMBINATION THERMOMETER, MIRROR, AND REFLECTOR DEVICE

Benjamin Putterman, Brooklyn, N. Y., assignor to Yankee Metal Products Corp., Norwalk, Conn., a corporation of New York

Application July 15, 1941, Serial No. 102,154

Term of patent 14 years

To all whom it may concern:

Be it known that I, Benjamin Putterman, a citizen of the United States, residing at Brooklyn, county of Kings, and State of New York, have invented a new, original, and ornamental Design for a Combination Thermometer, Mirror, and Reflector Device, of which the following is a specification, reference being had to the accompanying drawing, forming a part thereof, and in which:

Figure 1 is a front view of a combination thermometer, mirror and reflector embodying my new design.

Fig. 2 is a side elevational view of the device shown in Fig. 1.

Fig. 3 is a rear elevational view of the device shown in Fig. 1.

Fig. 4 is an end elevational view of the device.

The characteristic features of my design reside in the specific offset reflector-backed thermometer member in its relation with the mirror and mirror arm as shown in full lines in the drawing.

I claim:

The ornamental design for a combination thermometer, mirror, and reflector device, as shown and described.

BENJAMIN PUTTERMAN.
